UNITED STATES PATENT OFFICE.

HENRY WILLIAM TEMPLETON, OF BALACLAVA, VICTORIA, AUSTRALIA.

ACCOUNT OR LEDGER CARD IN BOOKKEEPING.

No. 864,872.

Specification of Letters Patent.

Patented Sept. 3, 1907.

Application filed September 8, 1906. Serial No. 333,776.

To all whom it may concern:

Be it known that I, HENRY WILLIAM TEMPLETON, a subject of the King of Great Britain, residing at 93 Grosvenor street, Balaclava, in the State of Victoria, Australia, have invented certain new and useful Improvements in Account or Ledger Cards in Bookkeeping; and I do declare the following to be a full, clear, and exact description of the invention, such as will enable others skilled in the art to which it appertains to

make and use the same.

This invention has been devised to provide improvements in the system of keeping accounts according to what is known as the "card system" wherein tabulated and enumerated cards are kept as records of the accounts standing between debtor and creditor in trade matters, and to save the time and labor usually employed in rendering monthly a/c statements to customers in trade and also time and labor in connection with ledger trial balances.

20 In order that my invention may be the more easily understood reference may be made to the accompanying drawings, in which—

Figure 1 is a view showing the card and two leaves or slips and the carbon sheet (both hereinafter referred to) 25 in position. Fig. 2 is a view of the inner or under leaf or slip after having been torn off and ready for despatching to the customer, while—Fig. 3 is an edge view of both leaves or slips with their upper edges separated and the gummed edge attached.

30 In these drawings A is a card preferably but not arbitrarily about 8 inches in length by 6 inches in depth and having at its bottom in the center a bite out or gap B for securing it to the filing box or machine. At the top right hand corner of the said card A I place two 35 small ruled divisions C and D the part C having the words "Card No." to indicate number of card and D having the word "Register No." to indicate the register number of customer. In connection with such card I use each month a transfer sheet doubled or folded to

40 form two leaves or slips E, P, the folded portion being at the top and the whole being preferably about 8 inches in length by 5 inches in depth. In the under or inner one E (see Fig. 2) is printed at the top the name of the firm supplying the goods, for instance, Smith & Com-

45 pany, preferably in the center and on the right hand side the address of such firm, the left hand side being devoted to other information about the warehouse &c. Directly underneath the address of the firm is a blank dotted line F with the figures 19.... at the end thereof so 50 that such line may be filled in with the year and date G when required, and beneath such line are the words "Average date", with a dotted blank line H at end thereof for filling in such average date when required.

55 Beneath the name of the firm, but slightly towards the left hand side, is a circumscribed space I, wherein it is intended that the name of the buying firm, say

Jones & Company, is to appear; the remainder of the sheet or slip E is ruled across longitudinally, the top lines J being doubled after the manner of a book of account, and provided with vertical columns K for dates 60 and items, the folio, the goods, (with the words "excluding sugar"), the next column L being for sugar, and a column M for duty and net cash items, a column N following for the total debit and a final column O for credits. At the bottom is an intimation to the 65 debtor to return the statement when remitting payment.

The front half or slip or sheet P of the folded sheet hereinbefore referred to contains all of the information and statements hereinbefore described, with the exception of the name, address and heading of the firm; Smith & Co., and the bottom intimation as to returning the statement.

I desire it to be distinctly understood that the circumscribed area I in which the name Jones & Co. is 75 to be written has a corresponding circumscribed space R on the front leaf or slip P so that it, the date, and all the other matters hereinbefore referred to, will be precisely over the similar matters on the back leaf or slip. The left hand inner edges of the leaves or slips E, P, 80 are gummed together at S but the back or inner one has a line of perforation S' running alongside such gummed line so that the whole of the back leaf or slip may be freely torn off from the front one.

In operation a sheet of carbon T (copying or plain) 85 is inserted between the front and back leaves or slips P and E with its copying face pointing downward on to the face of the back page E, the clerk writes the name of the firm Jones & Co. in the circumscribed blank space R on the front page P with a hard or indelible 90 pencil, pen or the like instrument. He also writes in the date G, and if necessary the average date blank; he then fills in on the various columns K, L, M, N, O, the matters for which the account is rendered, in same manner as is usually employed posting in ordinary 95 book ledgers. At the expiry of each month he makes the necessary additions and shows the debit or credit balance of the account, as the case may be. He then removes the carbon sheet T, tears out the back leaf or slip E and sends the same to the debtor (Jones & Co.). 100 The front leaf or slip P (together with the gummed remaining strip S) of the back leaf will remain gummed to the card which is then placed in the filing box drawer or machine for future reference.

It will be seen from the above description that where 105 my invention is employed an exact carbon copy of the ledger items is rendered monthly by the firm Smith & Co. to their customers and that much time and labor is saved errors avoided and fraud by collectors prevented. It will be seen also that each account has the 110 balance struck for the purpose of a monthly "trial balance" without any further labor.

While the front leaf or slip P is being filled in by the clerk one or more simple clips may be used on the right hand side edges of the card and the two leaves or slips to hold same together.

- 5 I would have it understood that I may add more than two of such leaves or slips, should more than one copy be required, or where the debit account has to be rendered in duplicate or triplicate, or where branch houses of business require same, in which case of course I use 10 more than one carbon sheet as T for the purpose of carrying my invention into effect.

The size of the card and the leaves or slips will of course be adjusted to suit the firms business as will also the various columns and headings.

- 15 One card may carry a number of the record front pages P, so as to extend such records for a year or more.

Having thus described my invention, what I claim and desire to secure by Letters Patent is—

1. A device of the character described comprising a pair 20 of leaves or slips having printed matter and blank spaces substantially in duplicate, and a card to which said leaves or slips are attached at one edge, the lower leaf or slip being weakened near its attached edge whereby it may be detached, leaving the upper leaf or slip attached to the 25 card.

2. A device of the character described comprising a pair of leaves or slips having printed matter and blank spaces substantially in duplicate, and a card to which said leaves or slips are attached at one edge, the card exceeding the

leaves or slips in width to provide a printing space on 30 the card that is not covered by the slips, the lower leaf or slip being weakened near its attached edge whereby it may be detached, leaving the upper leaf or slip attached to the card.

3. The combination with a card having means whereby it 35 may be removably secured in a filing case, of a pair of leaves or slips having substantially duplicate printed matter and blank spaces, said leaves or slips being attached at one edge to the card, and one of them being weakened near its attached edge whereby it may be detached, leaving 40 the other attached to the card.

4. A device of the character described, comprising a card and a folded sheet attached thereto, the under leaf 45 of the folded sheet having a line of perforations near its attached edge.

5. A device of the character described comprising a card and a folded sheet attached thereto, the under leaf 50 of the folded sheet having a line of perforations near its attached edge, said under leaf projecting beyond the upper leaf to form a space for a return request.

6. A device of the character described comprising a card and a folded sheet attached thereto along one end, the fold being at the top and weakened, the under leaf of the folded sheet having a line of perforations near its 55 attached edge.

In testimony whereof I have signed my name to this specification in the presence of two subscribing witnesses.

HENRY WILLIAM TEMPLETON.
